MANICURE TABLE

Esther Braverman, 1363 Yosemite St., Apt. 9.,
Denver, Colo.

Filed Aug. 19, 1959, Ser. No. 57,234

Term of patent 14 years

(Cl. D33—14)

I claim:

The ornamental design for a manicure table, as shown.
